UNITED STATES PATENT OFFICE.

GEORGE KNIGHT, OF BROCKTON, MASSACHUSETTS.

EYELETING-MACHINE.

No. 909,095.

Specification of Letters Patent. Patented Jan. 5, 1909.

Continuation of application filed April 22, 1902, Serial No. 104,109. This application filed July 11, 1903. Serial No. 165,084.

To all whom it may concern:

Be it known that I, GEORGE KNIGHT, a citizen of the United States, residing at Brockton, in the county of Plymouth and 5 State of Massachusetts, have invented an Improvement in Eyeletting-Machines, of which the following description, in connection with the accompanying drawings, is a specification, like letters on the drawings representing like parts.

10 This invention has for its object the production of a novel eyeletting machine.

15 My invention is illustrated in a machine for setting a plurality of eyelets of each cycle of operation of the machine.

Heretofore a plunger contained in one of the pair of sets has been used to pick off from a raceway an eyelet to be set, and 20 punched stock having been put on the plunger, the set has been moved to set the eyelet. So, also, an eyelet has been put by hand upon a plunger, and the plunger holding the eyelet has been moved to co-act with a hollow punch to punch a hole through the 25 stock, and the sets have thereafter been operated to insert an eyelet in the punched hole, and upset the eyelet in said hole.

In seeking to improve the efficiency of eyeletting machines, I have devised a machine 30 comprising a series of top and bottom sets, a plunger, and a punch, said plunger and punch normally occupying a position in the same vertical plane. The plunger is actuated to enter the eyelet at the end of a 35 raceway, and take the eyelet therefrom, after which the plunger holding the eyelet rises toward the punch and upper set.

The plunger holding the eyelet is so shaped 40 as to coact with an edge of the punch, and cut a hole in the stock, and thereafter as the sets are actuated they force the eyelets from the plungers into the stock, delivering the eyelets about the punch, and thereafter the sets acting in usual manner set the eyelets in 45 the stock.

The end of the plunger is shaped to present a rounded projection rising from a shoulder, said projection as the plunger rises entering unerringly the endmost eyelet of 50 the plurality of rows of eyelets at the delivery end of the raceway, after which the raceway is moved leaving the eyelets surrounding the plunger, the heads of the eyelets resting against the upper end of the lower or 55 low sets. After the rounded ends of the

plungers enter the eyelet, as stated, the plungers are further moved causing said rounded projections to enter the holes in the punches thus centering the plungers with relation to the punches, the movement of 60 the plungers being continued until the shoulders of the plungers at the base of the rounded projections co-acting with the cutting edges of the punches cut holes in the stock to be entered by the eyelet. The 65 diameter of the shoulders at the base of said projections is substantially as large as the external diameter of the punch, the plunger consequently acting as a guide for the eyelet as it is being forced therefrom by the lower 70 set to surround the punch prior to and during the process of upsetting the eyelet in the stock.

In the machine in which I have represented my invention to set a plurality of eyelets at one and the same cycle of operation, 75 the plungers and lower sets are moved in different times to perform the results required of them.

The invention to be herein described and 80 claimed is not, however, limited to the exact shape shown for the said rounded extremity or the projection that enters and picks off the eyelet from the raceway, as the same may be varied to effect the result herein aimed at 85 and yet not depart from my invention that I intend to claim broadly.

Figure 1 of the drawing represents in front elevation, partially broken out, a sufficient portion of an eyeletting machine to enable 90 my invention to be understood; Fig. 2 is a side elevation of the parts shown in full lines in Fig. 1 looking toward the left of the drawing; Fig. 3 is a detail broken out to illustrate the plurality of under sets and 95 plungers; Fig. 4 is a sectional detail showing the plunger coacting with the punch tube to punch a hole in the stock for the eyelet; Fig. 5 is a section in the line x', Fig. 3; Fig. 6 is a top view detached of the 100 guide used to position the portion of the shoe to receive the eyelet; Fig. 7 is an inner side view of the parts shown in Fig. 6, and Fig. 8 is a section in the dotted line x², Fig. 7.

The framework shown consists essentially 105 of a base A having rising therefrom suitable standards A' having bearings for the main shaft A². This shaft is surrounded by a friction clutch pulley A³, of any usual construction and under the control of a device A⁴ 110

that may be actuated by a treadle to start or stop the shaft.

The main shaft A² has fast on it as herein shown two like eccentrics A⁵, and an eccentric A⁶, and said shaft has also a cam A⁷.

The cam A⁷ acts through a suitable lever B having its fulcrum at B⁷ to reciprocate the raceway B² carrying the eyelets, the upper end of said raceway being movable in a suitable hopper B³ in which the eyelets are put in bulk.

The raceway is and may be of usual construction, and as shown it is adapted to contain a series of grooves to deliver a series of eyelets, a suitable spring 2^X at the lower end of the several compartments of the raceway coacting with each row of eyelets to maintain them on the raceway until taken therefrom positively.

20 The eyelets contained in the hopper are kept agitated by any usual agitator carried by a shaft B⁴.

The framework has rising from it a suitable stand C having a stud C' that serves as a fulcrum for two like levers C², actuated by straps embracing the eccentrics A⁵, and an intermediate lever C³ that is actuated by a link embracing the eccentric A⁶. The framework has an overhanging neck C⁴ suitably recessed to receive a block D held therein by a suitable locking device D' shown as an eccentric pin.

The block D has secured in it by suitable set screws D² a series of upper sets D³, and a series of punches D⁴, each upper set and punch having a central passage as a, the upper end of which terminates at a' in a discharge opening for pieces of leather punched from the stock in forming eyelet holes, said punchings entering a space a² in a box a³ connected by suitable screws a⁴, one of which is shown in Fig. 2 with the overhanging part C⁴ of the framework.

Viewing Fig. 4 it will be seen that the shoulder a⁵ of the upper set D³ acts against the reduced end or point of the eyelet, and that the lower circular edge of the punch D⁴ extends sufficiently far from the shoulder a⁵ of the upper set to receive and sustain each eyelet as it is being upset.

The sharp edge of the punch, shown as integral with the upper set, coacts with the shoulder or seat b located at the base of the rounded projection or extremity b' of the plunger b^X, said extremity being shaped to enter unerringly, as will be described, the large or flanged end of an eyelet held at the lower end of the raceway, the eyelet surrounding the plunger thus enabling the latter to always remove the eyelet from the raceway as the raceway is retracted. In its further movement the rounded extremity of the plunger enters and substantially fills the hole in the punch D⁴ and centers the plunger 65 with relation to the punch. As the raceway

is moved backwardly in usual manner the eyelets drop therefrom and surround the plunger, and the head ends of the eyelets are arrested while the head enters the upper ends of the lower sets b². As the rounded projection enters the hole in the punch the shoulders of the plungers meet the circular cutting edges of the punches and co-acting therewith cut clean holes in the stock for the reception of the eyelets.

70 Each plunger b^X is extended through a hole in one of a series of under sets b², the shanks of which are attached by suitable set screws b⁵ in a bar b³, said bar being connected with a sliding cross head b⁴ by means of a 75 suitable set screw b⁶.

Each plunger b^X is extended through a hole in one of a series of under sets b², the shanks of which are attached by suitable set screws b⁵ in a bar b³, said bar being connected with a sliding cross head b⁴ by means of a 80 suitable set screw b⁶.

The lower ends of the plungers b^X are shown as having heads c that normally rest against a cross bar c' extended through a space c² in the cross head b⁴. The cross bar 85 has suitably secured to it as by rivets c³ posts c⁴, shown best in Fig. 3, that are extended through suitable holes, see Fig. 1, in the projection or boss c⁵ extended from the framework A. The boss is slotted vertically to 90 receive the cross head b⁴, and a suitable cover plate as d held in place by screws d' maintains said cross head b⁴ in its operative position.

The lower ends of the posts c⁴ are slotted, 95 and in said slots are pivoted the upper ends of links d² in turn jointed with the outer ends of the two like levers C² actuated by said eccentrics A⁵.

The cross head b⁴ has at its lower end, see 100 Fig. 3, two ears provided with holes for the reception of a stud g, see dotted lines Fig. 1, that serves as a pivotal connection for a link g', in turn connected with a pin g² loose in suitable holes in the outer end of the lever C³ actuated by the eccentric A⁶ of the shaft A².

The upper portion of the boss c⁵ extended from the framework, supports a plate e that 110 partially covers the lower sets and plungers, said plate being pivoted at one end by a stud screw e² entering a hole e' in an ear of said plate, the ear at the opposite end of said plate having an open slot e³ that is entered by a clamp screw e⁴. The plate e has applied 115 to its inner side, see Fig. 7, by screws f narrow plates f' to constitute, with the part e^X of the plate e, guideways for the feet f² of gages f³, f⁴, said feet, as herein represented, overlapping one the other, see Figs. 7 and 8, 120 and each foot has an inclined slot 12, said slots being directed oppositely. The narrow plates f' have attached to them by screws 13 a slotted plate f⁵ having a series of teeth or projections 16 that may be engaged by the 125 edge of a block 17 having extended from it a threaded post 18. Said post, after passing through one of the diagonal slots 12 in each of the feet f² and through a vertical slot 19, see Fig. 1, in the part e^X of the plate e, has 130

applied to it preferably a washer 20, a spring 21 and a nut 20^x, the nut acting through the spring to hold the post and block 17 yieldingly. By pressing the nut 20^x inwardly the 5 post may be slid in the slot 19 and the slots 12 to thereby move the gages f^3 and f^4 away from or toward each other preparatory to the setting of a series of eyelets.

To locate the work for setting the eyelets I 10 take hold of the work and place the finger co-operating with the thumb holding the work against the outside of one or the other of said gages, according to which part of the work, as the right or left hand portion of the top of 15 a shoe, is being provided with eyelets. The work will also be grasped between the thumb and finger of the other hand, this being desirable because usually the work is pliable, and by engaging the same between both 20 hands it is possible to securely hold the work taut under the sets and with the edge of the work in proper position with relation to the gages or stops as 22 or 23, according to the requirements of the work, each gage having a 25 plurality of such stops.

If the eyelets are to be equidistant from the edge of the material, the said edge may rest against either the two faces 22 or the two faces 23, according to the distance it is desired to set the eyelets from the edge of the 30 material. If, however, it is desired to set the bottom eyelet at one edge farther from the edge of the material than the top eyelet at that edge, then I may put the edge of the 35 material against the face 22 of the gage f^4 and a portion of the edge of the material at a distance therefrom against the face 23 of the gage f^3 .

The gages f^3 and f^4 sustain the material in 40 position to be punched and to receive the eyelets in the punched holes.

Each upper set is acted upon by a strong spring h under the control of a screw h^1 . Washers h^2 are interposed between the ends 45 of the set screws D^2 and the bodies of the top sets, and in case of strain exerted on said upper sets or their connected punches, greater than they can or should bear, the springs will yield.

50 In operation let it be assumed that the raceway has been supplied with eyelets, that the lowermost eyelet in each raceway groove is held by a spring 2^x, that the material to be provided with eyelets is in position with its 55 edge against one or the other face of the gages f^3 , f^4 , and that the upper and lower sets are in the position Figs. 1 and 2. The machine will now be started, and immediately the eccentrics A^5 will cause the cross 60 bar c' to act and project the plungers to their fullest extent from the lower sets that said plungers may enter the row of endmost eyelets of the raceway, and the lever B' is then actuated to withdraw the raceway and leave 65 an eyelet surrounding each plunger.

The punches D^4 occupy at all times positions in line with the path of movement of the plungers, and as the plungers b^1 and sets b^2 continue to rise, the upper end of the plunger surrounded by an eyelet meets the underside of the stock, forcing the same against the lower hollow ends of the punches D^4 , and said plungers coacting with said punches punch a series of holes in the stock. During this operation the ends of the plungers enter 70 slightly the open ends of the punches, and the shouldered portions of the plungers meet substantially the circular cutting edges of the punches.

Viewing Fig. 4 it is supposed that the series of holes have been punched in the stock, and it will be seen that an eyelet surrounds the plunger below said end, and that the plunger is in position to act as a guide for the eyelet as the end of the eyelet passes from 80 the plunger into the material and about the outer side of the punch. As soon as the plungers that are moved positively by the cross bar c' , instead of being sustained by springs as usual, have coacted with the punches to punch a series of holes in the material, the upward movement of the plungers is stopped, as in Figs. 3 and 4, but the cross-head b^4 continues to rise, causing the under sets sustaining the heads of the eyelets to act 85 and force the eyelets into the holes made in the material, forcing the small ends of said eyelets against the shoulders a^5 of the upper sets, thus clenching the eyelets in the material, and the eyelets having been set, the 90 lower sets and plungers are lowered into their normal positions.

I have shown my invention applied to a gang eyeletting, but it is obvious that my invention might be practiced to advantage in 105 an eyeletting machine having but one bottom and top set, a plunger, a punch and a raceway.

I believe that I am the first to provide a machine of this class with independent gages 110 having each an edge guiding face by which the edge of the material may be set in or out of line with a line intersecting all the punches to thereby provide for inclining the line of eyelets with relation to the edge of the material, or in other words, spreading the lowermost eyelets of the two series.

This invention is not limited to the exact shape shown for the end of the plunger, nor to the exact means illustrated for controlling 120 the position of the gages.

It will be noticed that the punches D^4 extend for a considerable distance beyond the shoulder a^5 of the set D^3 , that acts against the small end of the eyelet. Elongating the 125 punch as shown enables the eyelet being set to surround the punch and be guided thereby during the operation of setting the eyelets. This is necessary especially when a plurality of eyelets are being set at one oper- 130

ation, as the long punches act as positive guides in preventing any undue movement of the work while the eyelets are being upset therein.

5 Pointing or rounding the extremity of the plunger greatly facilitates and insures the unerring entrance of the plunger into the eyelet at the end of the raceway.

This application is a continuance of my application Serial No. 104,109, filed April 22, 1902.

Having described my invention, what I claim and desire to secure by Letters Patent is:—

15 1. In an eyeleting machine, a top-set comprising a bar presenting at its end a punch constituted as a hollow tube with a cutting edge, said bar having a shoulder at a distance from the cutting edge to permit the 20 eyelet being set to be moved on to and to surround the punch, combined with an under-set comprising a hollow bar, the upper end of which is adapted to sustain the enlarged end of the eyelet to be set, and a spindle movable 25 inside said bar, said spindle having near its upper end a horizontal shoulder from which rises a protuberance having an upwardly rounded point to readily enter the eyelet, the

horizontal portion of said shoulder coacting with the circular edge of the punch to cut a 30 hole in the stock, the upwardly rounded point of the spindle above said shoulder entering said eyelet and hollow tube of the punch in advance of the cutting action of the punch, whereby said spindle is centered with relation to said punch. 35

2. In an eyeleting machine, means to present a series of eyelets, means to punch a series of holes in material, means to set a series of eyelets in said holes, gages to sustain the 40 material to be punched preparatory to receiving eyelets, said gages presenting a plurality of faces to provide for setting the eyelets at one end of the series at a greater distance from the edge of the material than the 45 eyelets at the other end of the series, and means to move said gages toward and from each other to adapt the gages to the work to be done.

In testimony whereof, I have signed my 50 name to this specification, in the presence of two subscribing witnesses.

GEORGE KNIGHT.
